UNITED STATES PATENT OFFICE.

WILLIAM A. PERKINS, OF PORTLAND, OREGON, ASSIGNOR TO C. W. RAYNOR, OF PORTLAND, OREGON.

COMBINATION EXPANSIBLE GARMENT-STRETCHER.

1,282,283.

Specification of Letters Patent. Patented Oct. 22, 1918.

Application filed March 3, 1915. Serial No. 11,666.

To all whom it may concern:

Be it known that I, WILLIAM A. PERKINS, a subject of the King of England, residing in the city of Portland, county of Multnomah, and State of Oregon, have invented 5 certain new and useful Improvements in Combination Expansible Garment-Stretchers, of which the following is a specification.

My invention relates to garment stretchers, and more particularly to a combination stretcher, adapted for use in baby stockings and shirts after they have been washed, for the purpose of stretching them while they are drying, and thus preventing 15 them from shrinking.

Among the salient objects of my invention are,—to provide a combination stretcher which can be used both for stockings and for shirts, and which is capable of adjustment, 20 so that it can be used with various sizes of stockings and shirts, thus providing a stretcher which can be used for small garments, and which can be adjusted from time to time to adapt it to larger garments, as required, thus avoiding the necessity of buying a stretcher for each size of garment worn, and to provide a combination article of 25 the character referred to, which can be cheaply manufactured and sold for a reasonable price.

In order that others may thoroughly understand my invention, I have illustrated in the accompanying sheet of drawings one practical form thereof, which I will now describe.

Figure 1 is a side elevation of a combination stretcher embodying my invention, adjusted, as shown in full lines, for a small size of garment, and with one side thereof 40 adjusted, as indicated in dotted lines, to show the expanded adjustment thereof for larger garments; and

Fig. 2 is a sectional view taken on line 2—2 of Fig. 1.

Referring now more in detail to the drawing, the stretcher comprises a two-part body, the parts of which are designated 1 and 2, hinged together at 3, and provided at their lower ends with foot forms, 1^a and 2^a, as

shown in full lines. Two auxiliary body members 4 and 5, having at their lower ends foot forms, 4^a and 5^a, similar to the foot forms, 1^a—2^a, and adapted to register therewith when in their folded positions, are pivotally connected, as at 4^b and 5^b, to the 55 foot forms 1^a and 2^a, respectively, so that when said members 4 and 5 are moved laterally from the members 1 and 2, as indicated in dotted lines, the two foot forms 2^a and 5^a, for example, assume the positions indicated by the solid and dotted lines, at the right hand side of Fig. 1, the two together thus adjusted making a larger foot form, as will be clearly understood from the drawing.

Pivots attached to the upper ends of the members 1 and 2 are two arm members 6 and 7, provided at their outer ends with adjustment holes 6^a and 7^a, and intermediate their ends have cam-like portions 6^b and 7^b. Connecting arms 8 and 9 are pivotally attached to the upper ends of the members 4 and 5, and are adapted to be adjustably connected at their outer ends to the outer ends of the arms 6 and 7, as indicated. Thus in 75 adjusting the device for garments of a larger size, the arms 8 and 9 are detached from the arms 6 and 7 and are moved outwardly and attached nearer to the outer ends of the arms 6 and 7, as indicated by the dotted line 80 positions of the members 5, 9 and 7.

It will readily be seen that the stretcher is adapted both for stockings and shirts. The arms 6 and 7 and the connecting members 8 and 9, are adapted to be inserted into 85 the sleeves of the shirt, while the body of the shirt is stretched around the members 4 and 5. It will also be seen that as said members 4 and 5 are moved apart, they will be adapted to stretch shirts having a larger 90 bust measurement.

The two halves of the device can be folded toward each other to facilitate the application of the shirt thereto, and when the arms 8 and 9 are disconnected at their outer ends 95 from the arms 6 and 7, the parts can be folded together in compact form for shipment. The upper ends of the arms 4 and 5

are preferably grooved and adapted to have a sliding, interfitting engagement with the arms 6 and 7, and with the cam portions 6^b and 7^b thereof, as the parts are adjusted outwardly to the position indicated in dotted lines.

It will also be apparent that if the arms 6 and 7 are raised slightly, the members 4 and 5 will be correspondingly moved outwardly, and the member 8 moved away slightly from the arm 6, as indicated in dotted lines at the left hand side of Fig. 1, thus giving a slight expansion movement to the body member 4 and the connecting arm member 8, without any change of the connection between the outer end of the member 8, and the outer end of the member 6.

I am aware that many changes can be made in the details of the invention as here shown for purposes of illustration without departing from the spirit thereof, and I do not, therefore, limit my invention to the particular form here shown, except as I may be limited by the hereto appended claims.

25 1. I claim:

1. A garment stretcher of the character referred to, comprising a two-part stocking-receiving body, the parts of which lie flatwise together and are movable edgewise relative to each other, whereby one part projects at one side and forms one operating edge of said body, and the other part projects at the opposite side and forms the opposite operating edge of said body.

35 2. In a garment stretcher, a body member having a foot form at its lower end, an auxiliary body member having a foot form at its lower end, said foot forms being pivoted flatwise together in register with each other, whereby as said body members are moved apart, said foot forms are moved out of register with each other, and together constitute an expanded foot form.

3. A garment stretcher of the character described, comprising a two-part body, each part of which is provided at its lower end with an expandible foot form composed of two flat members occupying adjacent planes, and movable relative to each other and adapted to receive a stocking thereon, and each part of which is provided at its upper end with a laterally expandible arm structure, adapted to receive the arm of a garment, substantially as described.

55 4. A combination expandible garment stretcher, comprising a two-part body, each part of which is expandible laterally and provided at its lower end with an expandible foot form composed of two flat members movable relative to each other in adjacent planes, adapted to receive a stocking, and at its upper end with an expandible arm structure, adapted to receive the arm of a gar-

ment placed thereon, said body portions being adapted to stretch the body of said garment.

5. A combination expandible garment stretcher of the character referred to, comprising two body portions hingedly secured together, and each comprising two adjustable members provided at their lower ends with foot forms, and at their upper ends with arm structures pivotally connected thereto, all of said parts being adjustable simultaneously to expand or contract the foot forms, the body portions, and the arm structures, substantially as described.

6. A combination expandible garment stretcher of the character described, comprising two body members hinged together and provided at their lower ends with foot forms and at their upper ends with laterally projecting arm members pivotally attached thereto, and auxiliary body members, having foot forms at their lower ends, and pivotally connected to the foot forms of said first body members, so as to normally register therewith, and adjustably connected at their upper ends, by means of connecting members, to the outer ends of said first arm members, whereby to simultaneously adjust said foot members, said body members, and said arm members, substantially as shown and described.

7. In a garment stretcher, in combination, a body member provided at its lower end with a foot form, an arm member pivoted to the upper end thereof, an auxiliary body member provided at its lower end with a foot form and pivotally connected to the foot form of said first body member, a second arm member pivotally connected to the upper end of said auxiliary body member and at its outer end adjustably connected to the outer end of said first arm member, whereby the adjustment of said second arm member operates to expand said arm members, said body members and said foot form.

8. A garment stretcher of the character referred to, comprising in combination, two body members hinged together and each provided at its lower end with a foot form, an arm member pivotally connected to the upper end of each of said body members, a pair of auxiliary body members each provided with a foot form at its lower end and pivotally connected to the foot forms of said first body members, and a second arm member pivotally connected to the upper end of each of said auxiliary body members and adjustably connected at its outer end to the outer end of the corresponding first arm member, whereby the adjustment of said second arm members operates to expand and contract said body members and said foot forms, substantially as described.

9. In a garment stretcher of the character referred to, a flat foot form, an auxiliary flat foot form pivotally mounted flatwise thereupon and in normal register therewith, 5 said auxiliary foot form being adapted to be moved relative to said foot form, whereby, in combination therewith, to increase the breadth through the ankle portion and the

instep portion of said foot form, substantially as described. 10

Signed at Portland, Multnomah county, Oregon, this 26th day of February, 1915.

WILLIAM A. PERKINS.

In presence of—

C. W. RAYNOR,

I. M. GRIFFIN.
